(57) **CLAIM**

The ornamental design for an ear cleaner handle as shown and described.

DESCRIPTION

Ear cleaner handle

FIG. 2.1 is a left elevation view of an ear cleaner handle; FIG. 2.2 is a front perspective view thereof;

FIG. 2.3 is a right elevation view thereof;

FIG. 2.4 is a front elevation view thereof;

FIG. 2.5 is a rear elevation view thereof;

FIG. 2.6 is a top plan view thereof, expanded to clearly show the features thereof; and

FIG. 2.7 is a bottom plan view thereof, expanded to clearly show the features thereof.

The dash-dash broken lines shown in the drawings depict portions of the ear cleaner handle that form no part of the claimed design.
